(57) CLAIM

The ornamental design for a camera mount kit substantially as shown and described.

DESCRIPTION

FIG. 1 is a front, left, top perspective view of a first part of a camera mount kit;

FIG. 2 is a front view of the first part of the camera mount kit of FIG. 1;

FIG. 3 is a back view of the first part of the camera mount kit of FIG. 1;

FIG. 4 is a left view of the first part of the camera mount kit of FIG. 1;

FIG. 5 is a right view of the first part of the camera mount kit of FIG. 1;

FIG. 6 is a top view of the first part of the camera mount kit of FIG. 1;

FIG. 7 is a bottom view of the first part of the camera mount kit of FIG. 1;

FIG. 8 is a front, left, top perspective view of a second part of the camera mount kit;

FIG. 9 is a front view of the second part of the camera mount kit of FIG. 8;

FIG. 10 is a back view of the second part of the camera mount kit of FIG. 8;

FIG. 11 is an enlarged view of a left side view of the second part of the camera mount kit of FIG. 8;

FIG. 12 is an enlarged view of a right side view of the second part of the camera mount kit of FIG. 8;

FIG. 13 is a top view of the second part of the camera mount kit of FIG. 8;

FIG. 14 is a bottom view of the second part of the camera mount kit of FIG. 8; and,

FIG. 15 is a front, left, top perspective view of the camera mount kit including the first part and the second part.

The dot-dash broken lines in the drawings depict portions of the camera mount kit that form no part of the claimed design.

1 Claim, 15 Drawing Sheets
